(57) **CLAIM**

The ornamental design for a bag for a tricycle, as shown and described.

DESCRIPTION

FIG. 1 is a front side view of a bag for a tricycle of the applicant's design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 a left side view of the canopy on a tricycle.

The broken lines showing a tricycle are for the purpose of illustrating environment and form no part of the claimed invention.
